UNITED STATES PATENT OFFICE.

CHARLES A. SMITH, OF LOS ANGELES, CALIFORNIA.

CONCENTRATOR.

SPECIFICATION forming part of Letters Patent No. 772,540, dated October 18, 1904.

Application filed August 14, 1903. Serial No. 169,529. (No model.)

To all whom it may concern:

Be it known that I, CHARLES A. SMITH, a citizen of the United States, residing at Los Angeles, in the county of Los Angeles and 5 State of California, have invented new and useful Improvements in Concentrators, of which the following is a specification.

The object of my invention is to provide convenient and economical means to remove 10 the concentrates from the gangue while in a wet state. I accomplish this object by means of the device herein described, and shown in the accompanying drawings, in which—

Figure 1 is a plan view of a concentrator 15 embodying my invention. Fig. 2 is a side elevation thereof. Fig. 3 is a transverse section taken on line 3 3 of Fig. 1. Fig. 4 is an enlarged section of a fragment of the concentrating-table with the diverting-riffle secured thereon. Fig. 5 is an enlarged cross-section of the slide-gate, taken on line 5 5 of Fig. 6. Fig. 6 is a longitudinal section of the slide-gate.

In the drawings, A is the rectangular concentrator-frame.

B is the concentrator-table, suspended in the frame by the pivoted supports D and D', and is provided with the usual means to impart thereto a shaking motion through the 30 driving-pulley C. This table has an inclination downward from the head B' to the tail end B'' thereof and is highest in its center, as shown in Fig. 3, the table sloping downward in both directions from the center. Disposed 35 along the center I have provided a number of discharge-ports E. These ports are arranged to be closed by the slide-gate F. On each side of the center of the table and running therefrom on an incline from the outer edge of the 40 concentrator-table and toward the center in the direction of the foot of the table and terminating at a point in close proximity to the center of the table are a number of concentrator-riffles G, the purpose of which is to 45 carry the concentratable portion of the pulp toward the center of the table when motion is imparted thereto, that the concentrate may pass down through the discharge-ports E into the concentrates-trough H, which is remov- 50 ably secured below the concentrator-table and

adapted to catch the concentrates as they pass through the discharge-ports E. These riffles are thickest at the end, terminating at the point adjacent to the center and gradually becoming thinner until the edge b of the concentrator-table is reached. The inclination upward of the table from the sides thereof to the center will have a tendency to carry the light material in the pulp from the center toward the sides; but the shaking motion of the table, together with the inclination of the riffles from the edge of the table toward the center and downward from the head to the tail, will have a tendency to carry the concentrates in the direction of the center of the table and deposit the same in the center, so that they will pass off through the discharge-ports E. These central discharge-ports E are closed by the slide-gate F, provided with the pivoted handle I, to which the connecting-link J is pivoted 55 at one end and pivoted to the slide-gate at the other. These gates are arranged to work in longitudinal guideways in the frame. By means of these slide-gates the discharge-openings E may be increased to any extent desired and may be entirely closed, if desired. 60

My concentrator is operated as follows: The pulp is fed to the head of the concentrator-table through the feed-chute K, being first deposited into the trough L, passing thence 65 over the rim M thereof onto the head B' of the table. The rocking motion of the table and the inclination downward thereof from the head to the tail will cause the pulp to pass down over the riffles on the top of the table, 70 the concentrates passing to the concentrator-trough H through the discharge-ports E as it works its way from the head to the tail of the table. By this arrangement as soon as any portion of the substance operated on is prop- 75 erly concentrated it will immediately pass through the discharge-port first reached into the concentrator-trough and relieve the concentrator-table of so much of the concentrates as pass therefrom, increasing thereby the capacity of the concentrator. 80

Having described my invention, what I claim as new, and desire to secure by Letters Patent, is—

The herein-described concentrator-table 85

elevated in the longitudinal center thereof, and having ports in its longitudinal center; riffles on the top of the table leading downwardly from the sides thereof to a point adjacent to the center; the riffles being low at the outer end and high at the inner end; and means to regulate the openings in the center for the discharge therethrough of the concentrates from the table as they are separated

from the gangue, and means to give a longitudinal swinging motion to the table.

In witness that I claim the foregoing I have hereunto subscribed my name this 7th day of August, 1903.

CHARLES A. SMITH.
